UNITED STATES PATENT OFFICE

2,133,316

AIR CLEANER

Herman E. Altgelt, South Bend, Ind., assignor to
Oliver Farm Equipment Company, a corpora-
tion of Delaware

Application March 18, 1935, Serial No. 11,571

7 Claims. (Cl. 183—24)

The present invention relates generally to air cleaners for internal combustion engines, but more particularly to an air cleaning device for vehicles such as the tractor and the like.

One of the primary objects of the present invention is to secure certain improvements and refinements over the construction of air cleaner described and claimed in my U. S. Letters Patent No. 2,033,368 issued March 10, 1936.

One of these refinements consists of providing a novel bowl shaped container which provides a comparatively small surface for the oil in the bottom thereof so that the oil will be more thoroughly agitated by the air as it is drawn there-
through.

A further object of the present invention is to provide a novel air cleaner container of the bowl shaped or inverted dome-like container which not only eliminates remote corners or places where the dirt may accumulate, but also provides a relatively enlarged air chamber in the top thereof to form in effect a temporary storage space of greater capacity for the cleaned air, after it has passed through the oil.

Another object of the invention is to provide a novel and improved air cleaner construction in which the mouth of the tube connecting the air cleaner container with the dirt receptacle is substantially larger than the discharge end of the air intake tube submerged in the oil.

A still further object of the invention is to provide a novel and improved air cleaner construction in which the air intake pipe thereof is so arranged as to prevent oil being discharged therethrough by reason of the engine backfiring.

A further object of the invention is to provide an improved air cleaner in which a novel duct located between the conduit leading from the cleaner proper to the carburetor is so arranged that any oil passing with the clean air into the duct will be condensed on the walls thereof and be returned to the cleaner proper.

These and other objects are accomplished by providing a construction and an arrangement of the various parts in the manner hereinafter described and particularly pointed out in the appending claims.

Referring to the drawing:

Fig. 1 is a transverse cross sectional view of my improved air cleaner showing the same mounted on the hood of an engine; and

Fig. 2 is a side elevational view of the same partly in cross section.

As previously pointed out, the present invention comprises certain novel improvements and

refinements over my aforesaid patent and for the purpose of illustration, I have shown the same in connection with a conventional form of engine hood generally indicated by the reference character 10. Formed as a part of and to the underside of the hood 10 by being soldered, welded or otherwise secured, is a bowl shaped or inverted dome-like container 11. This construction of container affords a very large area or space in the upper portion thereof beneath the hood so as to form in effect, a spacious temporary storage for the clean air. While the narrow bottom permits the oil generally indicated by the reference character 12, to cover a small area or surface affording a greater agitation of the oil resulting in a more efficient cleaning of the air. Located at the axial center of the container 11 and extending through an opening 13 of the hood 10, is an air intake pipe or conduit 14 which has its lower end reduced or constricted or in the form of a conically shaped extension as shown at 15. Mounted on the upper end of the intake pipe 14 is a removable cap 15 which is semi-spherical in shape. Located within the semi-spherical cap 15 and secured to the inner edge thereof is the conically shaped screen of fine wire mesh as shown at 16. The inner portion of this screen 16 has an outwardly protruding cylindrical portion as shown at 17 which is adapted to telescopically seat itself within the upper end of the conduit 14. The outermost portion of this cylindrical screen 17 is beveled inwardly as shown at 18. Secured at the axial center of the semi-spherical cap 17 is an oil measuring rod 19. Secured at a point adjacent the lower end of the intake conduit 14 as shown at 20 is an intake extension generally indicated by the reference character 21. This extension 21 of the air intake conduit 14 comprises a relatively flat conical section 22 at the upper end thereof which terminates in a downwardly extending converging wall as shown at 23 so as to form in effect a constricted opening which is submerged beneath the oil 12 in the bottom of the container 11. Extending from the lower end of the extension 21 across the bottom of the container 11 is a wire mesh or screen 25. Secured to and extending from the outer edges of the conical portion 22 of the extension 21 is an upper wire screen 26 which has its outer edge thereof secured at the inner wall of the container 11. Mounted between these screens 26 and 25 and extending around the extension 21 is a cleaning fibre generally indicated by the reference character 27. Secured to the bottom of the container 11 ad-

5 jacent to the opening 28 thereof is a tubular bracket 29. It will be observed that the mouth of this tubular bracket 29 as well as the opening 28 in the container is substantially twice the size of the opening 24 in the air inlet extension 21. Formed on the lower end of and communicating with the tubular bracket 29 is a vertically extending barrel portion generally indicated by the reference character 30, which in turn is provided with a valve seat 31. Reciprocally mounted in the threaded sleeve 32 mounted in the valve structure 30 is a valve 33 adapted to be actuated by a lever 34. This lever 34 in addition to controlling the valve 33 is actuated to retain 10 or disconnect a dirt receptacle or glass container 35 by oppositely disposed arms 36 in the manner clearly described and claimed in aforementioned patent. For that reason it is believed that a more detailed description of the same is unnecessary.

15 20 In order to facilitate the return of any oil which may be conveyed by the clean air passing from the upper portion of the air cleaner into the carburetor, I have provided a novel arrangement which includes a downwardly extending flange 37 surrounding an aperture in the hood 10 as clearly shown in Fig. 2 of the drawing. Connected to a second downwardly extending flange 38 formed around an aperture located rearwardly of the flange 37 is an upwardly projecting 25 30 conduit 39 which has its upper end as shown at 40 projecting slightly above the upper surface of the hood. The lower end of the conduit is connected to the carburetor in a manner well understood in the art. Extending over the upper 35 end of the conduit 39 and the opening 37 is a cap or covering 41 which establishes communication between the upper portion of the air cleaner and the conduit leading to the carburetor.

30 The operation of my air cleaner is as follows: 40 The air to be cleaned is drawn through the fine mesh wire or screen 16 underneath the cap 15 and is then drawn downwardly through the inlet pipe 14 and through the constricted opening located at the lower end into the enlarged extension 21, thence downwardly through the constricted opening 24 of the extension which is submerged below the surface of the oil 12. The incoming air sets up an agitation of the oil which saturates the fibre 27 in the process of cleaning 45 the air. As the air is being washed in this oil bath, the heavy particles and dirt settle downwardly and are directed by the curved sides of the bowl 11 into the relatively large opening 28 located in the bottom of the bowl 11 from where 50 they are conducted through the conduit 29 to the dust collecting receptacle 35. The upper portion of the container 11 is substantially larger than the lower portion thereof so as to establish in effect a relatively temporary storage space for the 55 clean air. This large storage space establishes a "quiet zone" for the clean air and permits a substantial part of the oil vapor to condense on the walls of the container before the air is passed into the carburetor. From this space the clean air is 60 drawn into the opening 37 through the cap 41 to the conduit 39 leading to the carburetor. In this connection it will be noted that any further condensation of the oil vapors upon the surfaces of the cap 41 will find its way back through the 65 opening and flange 37 into the cleaner proper. It will also be noted in connection with my improved cleaner, that by providing a conically shaped end 15' on the inlet conduit 14 and constricting the lower end of the extension as shown 70 at 21, any backfiring by the engine will not 75

cause a discharge of oil through the air cleaner.

From the above description it will be readily seen that I have provided certain novel and improved refinements of an air cleaner so that the same will more efficiently clean the air passing therethrough.

While in the above specification I have described one embodiment which my invention may assume in practice, it will of course, be understood that the same is capable of modification and that modification may be made without departing from the spirit and scope of the invention as expressed in the following claims.

What I claim is my invention and desire to secure by Letters Patent is:

1. An air cleaner comprising a bowl-like container, said container adapted to hold a liquid, an air inlet conduit extending into said container having one end thereof submerged in said liquid, and a dirt receiving conduit communicating with said container located vertically below and substantially larger than the lower end of said inlet conduit.

2. An air cleaner comprising a bowl-like container, said container adapted to hold a liquid, an air inlet conduit extending into said container, said inlet conduit having a constricted and an expanded portion intermediate its ends, the lower end of said inlet conduit submerged in said liquid, a dirt collecting receptacle carried by said container, and a conduit connecting said container with said dirt receptacle.

3. An air cleaner comprising an inverted dome-like container, said container adapted to hold a liquid, and air inlet conduit extending into said container and having its lower end constricted, an air inlet extension connected to said conduit having an expanded upper portion and a constricted lower portion, the lower end of said extension submerged in said liquid, and a dirt collecting receptacle communicating with the lower end of said container.

4. An air cleaner comprising a container having a constricted lower portion and an expanded upper portion, said container adapted to hold a liquid, an air inlet conduit extending into said container, and having its lower end constricted, an air inlet extension connected to said conduit having an expanded upper portion and a constricted lower portion, the lower end of said extension submerged in said liquid, and a dirt collecting receptacle connected to the lower portion of said container.

5. The combination of an air cleaner formed as a part of an engine hood, said container consisting of a reduced lower portion and an expanded upper portion, said container adapted to hold a liquid, an air inlet conduit extending through said hood into said container and having its lower end submerged in said liquid, an air exit conduit communicating with the upper portion of said container, and means forming the connection between said container and said last named conduit for returning the liquid condensed therein to said container.

6. The combination of an air cleaner formed as a part of an engine hood, said container consisting of a reduced lower portion and an expanded upper portion, said container adapted to hold a liquid, an air inlet conduit extending through said hood into said container and having its lower end submerged in said liquid, an air exit conduit communicating with the upper portion of said container, and means including a portion of said hood for forming the connection

between said container and said last named conduit for returning the liquid condensed therein to said container.

7. The combination of an air cleaner formed as a part of an engine hood, said container consisting of a reduced lower portion and an expanded upper portion, said container adapted to hold a liquid, an air inlet conduit extending

through said hood into said container and having its lower end submerged in said liquid, an air exit conduit communicating with the upper portion of said container, and a cap mounted on said hood forming the connection between said container and said last named conduit for returning the liquid condensed therein to said container. 5

HERMAN E. ALTGELT.
